UNITED STATES PATENT OFFICE

148,838

DESIGN FOR A SCORE TABLE

Robert I. Anderson, Grand Haven, and Bert Hoeker, Muskegon, Mich., assignors to The Brunswick-Balke-Collender Company, Chicago, Ill., a corporation of Delaware

Application March 13, 1946, Serial No. 127,452

Term of patent 14 years

(Cl. D34—5)

To all whom it may concern:

Be it known that we, Robert I. Anderson and Bert Hoeker, both citizens of the United States, residents, respectively, of Grand Haven, in the county of Ottawa, State of Michigan, and of Muskegon, in the county of Muskegon, State of Michigan, have jointly invented a new, original, and ornamental Design for a Score Table, of which the following is a specification, reference being had to the accompanying drawings, forming a part thereof.

Fig. 1 is a perspective view looking at the front of a score table or the like, showing our new design;

Fig. 2 is a perspective view thereof looking from the rear.

We claim:

The ornamental design for a score table, as shown.

ROBERT I. ANDERSON.
BERT HOEKER.
